US00D962932S

(12) United States Design Patent (10) Patent No.: US D962,932 S
He et al. (45) Date of Patent: * Sep. 6, 2022

(54) SMARTWATCH

(71) Applicant: SHENZHEN DO INTELLIGENT TECHNOLOGY CO., LTD., Shenzhen (CN)

(72) Inventors: An He, Shenzhen (CN); Peng Li, Shenzhen (CN)

(73) Assignee: SHENZHEN DO INTELLIGENT TECHNOLOGY CO., LTD., Shenzhen (CN)

() Term: 15 Years

(21) Appl. No.: 29/802,360

(22) Filed: Aug. 4, 2021

(30) Foreign Application Priority Data

Jun. 4, 2021 (CN) 202130354267.1

(57) CLAIM

The ornamental design for a smartwatch, as shown and described.

DESCRIPTION

FIG. 1 is a front and right side perspective view of a smartwatch showing our new design;

FIG. 2 is a rear, left and bottom side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in FIGS. 1-8 illustrate portions of the smartwatch that form no part of the claimed design.

1 Claim, 8 Drawing Sheets
